UNITED STATES PATENT OFFICE.

HENRY M. SARVANT, OF TACOMA, WASHINGTON.

COVER-FASTENER.

1,051,015.

Specification of Letters Patent. Patented Jan. 21, 1913.

Application filed May 4, 1912. Serial No. 695,180.

To all whom it may concern:

Be it known that I, HENRY M. SARVANT, a citizen of the United States, residing at Tacoma, in the county of Pierce and State 5 of Washington, have invented a new and useful Cover-Fastener, of which the following is a specification.

This invention relates to devices for fastening the cover of a tub, or other similar 10 shipping receptacle, and has for its objects to provide a fastening means which will be cheap and effective to make and to apply, and which will not penetrate through the tub walls into contact with the 15 contents thereof. I attain these and other objects by the devices illustrated in the accompanying drawing, in which—

Figure 1 is a perspective view of a tub with my improved fastening means in use 20 thereon; Fig. 2 is a similar view showing the fastening means released; and Fig. 3 is an enlarged section showing the special 25 form of staple used to attach the fastening means to the tub.

Similar numerals of reference refer to 30 similar parts throughout the several views.

This device is especially designed for closing tubs in which merchandise is shipped 35 from the factory or wholesaler to the retail dealer. Any desired form of tub may be used but I have illustrated the invention in connection with a circular tub 1 provided with two binding straps or hoops 2 preferably formed of wire. Four staples 3, 40 formed substantially as shown in Fig. 3, are driven into the side of the tub at four equidistant points therein, alternate staples being diametrically opposite to each other. Each staple 3 is formed of wire with its ends 45 pointed to enter the side of the tub, and has its lower portion practically at right angles to the adjacent point so as to form a driving head which, when the staple is driven home, comes in contact with the side of the 50 tub thus preventing its points from passing through the wall of the tub. The upper portion of the staple is bent away from the tub in a curve, forming a loop through which the handle and fastening wires may be passed. The handle wire 4 is passed across 55 the tub and is secured to two opposite staples 3 in the usual manner. The fasten-

ing means consists of a pair of wires, one of which 5, is securely fastened at both ends to two adjacent staples 3, one of the staples 55 being also used for one end of the handle wire 4, and is of such length as to pass to a point near the center of the cover 6 of the tub. The other wire 7 is fastened at one end to the staple 3 to which the other end 60 of the handle wire 4 is attached, and extends therefrom to the center of the cover and loops through the wire 5 and then passes to the last staple 3 to which it is removably secured by bending.

It is evident that this device requires very little material and also very little care in putting it together and that therefore it can be done quickly and cheaply and yet it effectually secures the cover in place during 70 shipment. Since the staples 3 do not penetrate the wall they do not come in contact with the contents of the tub. Further, no holes are made in the tub or its cover to allow air and dust to have access to the 75 contents, thus preserving the shipment in perfect condition as well as cheapening the package, since the staples are cheaper to install than holes are to make, and the wires 5 and 7 can be more readily threaded 80 through the staples than through holes. Also it will be noted that the wires 5 and 7 do not enter the tub at any place and therefore do not come in contact with the contents.

Having described my invention, what I claim is:

In a device of the class described, the combination of a tub having a cover therefor; four staples in the sides of said tub, each 90 having a loop extending outward from the side, and positioned so that alternate staples are diametrically opposite each other; a wire secured at its ends to two adjacent staples and extending toward the center of 95 the cover; and a second wire secured to one of the remaining staples at one end and looped through said first wire at the center of the tub and secured at its other end to the other remaining staple.

HENRY M. SARVANT.
